ASH RECEIVER FOR SMOKERS

Michael R. Wronski, Milwaukee, Wis.

Application July 29, 1932. Serial No. 626,102

1 Claim. (Cl. 131—51)

The invention relates to ash trays or receivers for the use of smokers, and comprises a portable device which may be placed upon the top surface of a desk or other support, or it may be inset in an opening in the top of a desk, arm of a chair, or be otherwise arranged as convenience may require.

The invention resides in a receiver or receptacle, in which ashes may be accumulated and stored from time to time. The receiver or receptacle is provided with a gate which is in the form of a flat plate pivotally mounted so as to stand normally at an angle to the vertical axis of the receiver or receptacle, in which position it will serve to act as a closure for the bottom or storage part of the receiver or receptacle. The said gate is pivoted to permit its being thrown from one side to the other, it functioning in either position, and is provided at its upper end with a rest upon which may be placed a lighted cigar or cigarette. The rest for the cigar or cigarette is in the form of a grooved support, bent at a right angle and secured at its inside angle to the gate, so that in either position of the latter, a rest with a horizontal trough is uppermost, is provided for the reception of a burning cigar or cigarette. Ashes and other refuse, accumulated on the upper or exposed side of the gate, may be dumped into the storage part of the receptacle, by merely turning over the gate.

The different constructions shown in the drawing will now be described in detail, and the novelty residing in the invention will be pointed out in the appended claim.

35 In the accompanying drawing:

Figure 1 is a vertical central sectional view through the invention and showing it in one of its forms, and as adapted to rest upon the top of a desk.

40 Fig. 2 is a view of the invention in side elevation, looking from the right of Fig. 1.

Fig. 3 is a vertical central sectional elevation, similar to Fig. 1, showing a modified form of the invention, adapted to be positioned in an opening in the top of a desk, arm of a chair, or other suitable support; and

Fig. 4 is a view from the right of Fig. 3, with a part of the receiver or receptacle broken out to show the manner of mounting the gate.

50 In the drawing, the numeral 10 indicates an ash receiver or receptacle, having a closed bottom, and finished at its top with an outwardly extending bead or flange 11, which preferably extends about the four sides of the receiver 10.

55 Associated with the receiver 10 is a tubular

member or section 12, slightly less in its transverse dimensions than the receiver 10, so as to be easily inserted therein and removed therefrom. The tubular member 12 is open at its lower end, but is provided at its upper end with an outstanding bead or flange 13, which latter is adapted to engage the bead or flange 11 of the receiver 10, and thus support the tubular member 12 within the latter, with a clear space in the lower end of the receiver 10, and below the lower end 60 of the tubular member 12, for storing an accumulation of ashes or debris.

A gate 14, in the form of a flat plate, having a width about equal to the distance between two opposite walls of the tubular member, is provided 70 upon its upstanding edges with opposite pivotal points 15, engaged in openings in the opposite walls of the tubular member. The gate 14 is adapted to stand in a diagonal position in relation to the vertical axis of the tubular member 12, 75 and act as a closure for the storage space below. As indicated in dotted lines, the gate is adapted to be turned on its pivots 15, into an opposite position, it then performing the same function.

Attached to the upper end of the gate, which projects slightly above the bead 13 of the tubular member, is a rest 16 for a burning or unconsumed cigar or cigarette. The said rest is formed as a channel or grooved member, bent transversely at its middle into the angular form shown. The 85 rest 16 is secured at its inside angle to the upper edge of the gate, by soldering or otherwise.

By thus constructing the rest 16 as an angular member, one arm of the latter will always be in horizontal position, in either position of the gate. 90 Ashes or debris falling upon the upper side of the gate, as conventionally shown in Fig. 3, may be passed into the storage space of the receiver 10, by simply throwing the gate over to the other side. By withdrawing the tubular member 12 and the gate from their position in the receiver 10, the accumulations in the storage space of the latter, may be emptied.

95 Figs. 3 and 4, illustrate a modification of the invention, in which the receiver 10 and the tubular member 12 are produced as one part, to form a receptacle 20, closed at its bottom, and provided at its open upper end with an outwardly extending flange or rib 21, whereby the receiver 100 may be supported in an opening in the top of a desk 22, arm of a chair, or other device. The mounting of the gate 14 in the receptacle 20, is 105 the same as has been already described in connection with Figs. 1 and 2, and the operation of 110

the gate 14 and the rest 16, is as before. The mounting of the gate 14 so as to be a part of the receptacle 20, will not interfere with the emptying of the latter, if the gate be swung to an intermediate position, so as to enable the accumulation to pass from the storage chamber.

In either of its closed positions, the gate 14 practically excludes the atmosphere entering the lower part of the receiver or receptacle, in consequence of which burning stubs dumped therein, will soon be extinguished.

Having thus described my invention, what I

claim and desire to secure by Letters Patent of the United States, is:

An ash receiver open at its upper end and provided with a pivoted gate normally standing in diagonal relation to the vertical axis of the receiver, the said gate being adapted to swing from one side to the other to close the receiver in either extreme position of the gate, and an angular rest supported on the upper edge of the gate and furnishing a support for a cigar or cigarette in either position of the gate.

MICHAEL R. WRONSKI.
